UNITED STATES PATENT OFFICE.

JOHN CLIFFORD, OF CHICAGO, ILLINOIS, ASSIGNOR TO THE L. WOLFF MANUFACTURING COMPANY, OF SAME PLACE.

WATER-CLOSET.

SPECIFICATION forming part of Letters Patent No. 335,895, dated February 9, 1886.

Application filed December 12, 1885. Serial No. 185,463. (No model.)

To all whom it may concern:

Be it known that I, JOHN CLIFFORD, of Chicago, in the county of Cook and State of Illinois, have invented new and useful Improvements in Water-Closets; and I do hereby declare that the following is a full, clear, and exact description thereof, reference being had to the accompanying drawings, making part of this application.

10 My invention relates to certain new and useful improvements in that kind of water-closets in which there is a side delivery-bowl, of porcelain or other frangible material, the neck of which has to be securely fastened in a water-tight manner to the cast-iron trunk, and in which there is also a metallic trunk or reservoir located beneath the seat of the closet and provided with a removable metallic cover.

Previous to my invention it has been customary in the manufacture of such closets to secure the neck of the bowl (with a packed joint) to a sort of supporting and coupling stand formed on the trunk-casting in various ways; but in all the prior constructions, so far as I know, there has always been great difficulty in effecting the jointure of the frangible bowl-neck, and the metallic trunk device in a manner at once simple, strong, durable, and perfectly water-tight.

30 I propose by my invention to provide the means for effecting a better, simpler, and more lasting water-tight joint between the bowl-neck and the trunk than has heretofore been attained to; and to this end my invention may be said to consist, primarily, in forming the metallic stand, that projects from the trunk, with a sort of semi-cylindrical (or semi-tubular) portion provided with a semi-annular groove or recess. In forming the neck of the 40 bowl with an annular bead, and in providing a semicircular retaining-strap or half-collar, that, by preference, also has a semi-annular recess in it, these parts being adapted to be put together, with a suitable plastic packing 45 between their adjacent surfaces, in such manner that the beaded portion of the bowl-neck will be encircled by the recessed portion of the metal stand and the grooved half-collar, when the latter shall have its ends bolted to 50 said stand, and so that the said bowl-neck will be securely and durably coupled in a perfectly

water-tight manner to the metallic trunk, with the delivery-opening of which said bowl-neck communicates, all as will be hereinafter more fully explained.

55 In the manufacture of such closets it has also been customary previous to my invention to have the metallic cover of the trunk secured to the latter by means of screws and nuts, after the usual fashion of bolting together iron 60 work in other structures; but this heretofore-employed means for and mode of fastening in place the cover of the trunk is objectionable, for the reason that in many places in which such closets are set up it is frequently very 65 inconvenient to get at and entirely remove the screws and their nuts, or to get at and tighten up the screws and nuts; and, furthermore, it is always undesirable to thus remove the screws from their nuts on account of these 70 parts getting mislaid while working around the closet so that they cannot be replaced when wanted.

75 My invention has for one of its objects to cure this objection in the structures heretofore made; and to this end my invention consists, secondly, in a novel construction of the lugs of the cover and trunk-top, with cut-outs through which the body of the bolt or screw may be passed laterally, and with upwardly- 80 projecting portions on the lugs of the cover, which hold the screw in place laterally when the latter is turned home, but which pass beneath the head of the screw when the latter shall have been slightly unscrewed, to permit 85 the extrication of the parts.

It also consists in an arrangement of the bolts and nuts with the trunk such that one side of each of the nuts will come to a bearing against the exterior surface of the wall of the 90 trunk and thereby be held from turning with the bolt in either screwing in or unscrewing the latter, and thus render unnecessary the use of any wrench in putting together or taking apart the devices to which the bolts and nuts 95 are applied, all as will be hereinafter more fully explained.

To enable those skilled in the art to which my invention relates to use water-closets containing one or all of these novel features of 100 construction, I will now proceed to more fully describe the several parts of my invention,

referring by letters to the accompanying drawings, which form part of this specification, and in which I have shown my invention carried out in that form in which I have so far 5 successfully practiced it, and which is the best now known to me.

In the drawings, Figure 1 is a perspective view of so much of a water-closet of the kind above alluded to as it is necessary should be 10 shown to illustrate the application to such a closet of the several features of my invention. Fig. 2 is a view in perspective (enlarged scale) of the bowl-neck, detached to better show its circumferential bead. Fig. 3 is a 15 partial or detail vertical section (same scale) through the center of the combined or coupled bowl-neck and its metallic support. Fig. 4 is a detail view in perspective of the lug-like devices of the trunk and its cover, drawn on 20 an enlarged scale, and with the parts securely fastened together, while Fig. 5 is a similar view, but with the screw slightly unscrewed, and showing how the cover may be removed without removing either the screw or nut. 25 Fig. 6 is a detail bottom view of the lug on the trunk and of part of the trunk, showing the relative arrangement of the nut and trunk-wall.

In the several figures the same part will be 30 found designated by the same letter of reference.

A is the bowl, and B the trunk or reservoir, of the closet, the said porcelain bowl and the metallic trunk being connected together by 35 the union of the neck *a* of the former with the coupling-stand *b* of the latter.

C is a metallic half-collar or semicircular band, the ends *c* of which are formed so as to be united with the lugs or ear portions *d* of 40 the stand by screw-bolts *e*, all as clearly shown.

The stand *b* is formed with a groove or recess at *f*, and the half-collar or band *C* has a similar groove at *g*, so that when these two metallic parts are bolted together their internal tubular surface contains a continuous annular groove adapted to accommodate or receive the annular bead or rib *h* on the external surface of the neck *a* of the porcelain bowl.

I represents any suitable packing, which 50 intervenes between the adjacent surfaces of the bowl-neck and of the metallic parts with which it is connected, and which is applied in a plastic condition at the time of setting up the closet, and subsequently hardens sufficiently 55 to insure the perfect water-tightness of the joint between the parts.

It will be understood that the neck of the bowl is seated and packed within and on the stand portion *b* of the trunk, with its annular 60 bead or rib *h* matched into the grooves *f* and *g* of the stand and half-collar, so that any endwise movement of the bowl-neck relatively to the metal parts with which it is coupled is effectually prevented, and it will be seen that 65 while all longitudinal movement of the coupled parts relatively is thus prevented the bowl is firmly supported and securely held in place.

otherwise by having its neck firmly clasped by the metallic clamping devices, which, however, encircle it with an interposed packing, 70 so that there is no danger or liability of fracturing the porcelain portion of the closet.

Of course the forms of the parts may be varied more or less, and the shape of the interlocking-groove in the metallic parts and bead 75 on the bowl-neck may be changed without departing from the novel structure to which the first part of my invention relates, and, if deemed expedient, more than one interlocking recess and rib may be employed. 80

As every plumber and other person skilled in the art knows, it is sometimes very awkward to get at the nuts (and hold them with a wrench) while unscrewing the bolts or screws used to fasten on the cover *H* of the trunk *B*, 85 and to avoid the necessity of thus holding the nut I place the nut *m* so that one of its sides will come to a bearing against the exterior surface of a portion, *n*, of the wall of the trunk, as clearly seen at Fig. 6. In other words, I place the 90 screw and its nut with their axes so near to the portion *n* of the trunk and make the nut *m* of such size that its corners cannot turn within the space between the nut and the trunk-wall. In this way the wall serves to 95 hold the nut against turning, and thus no necessity arises for the workman to hold the nut while manipulating the screws. The screws *o* are made, preferably, with screw-driver heads, as shown, and the lugs *p* of the cover 100 *H* are each cut out or slotted, as shown at *r*, and each formed with raised portions or projections *s*, so that when the screw *o* is turned home the cover is in place laterally in all directions, since the sides and bottom (or end) 105 of the cut-out *r* come against the body of the screw, while at the same time the upward projections *s* prevent any lateral movement of the parts relatively in the only direction in which such movement is not prevented by the 110 bearings of the screw's body against the walls of the slot or cut-out *r*; but whenever it may be desired to remove the cover *H*, it is only necessary to turn the screws *o* out until their 115 heads pass over the projections *s*, or, in other words, until the projections can pass beneath the screw-heads, when the cover may be slid along sufficiently to let the upper portion of the screw's body out through the slit or cut-away *r*, when of course the cover can be removed, the screw remaining in engagement with its nut, so that neither the screw nor the nut can get mislaid.

The novel features of structure by which this convenient result is accomplished will be 125 appreciated as quite a desideratum in water-closet contrivances, which, as before remarked, have often to be put up in places where and under circumstances such that great difficulty arises in getting at the cover fastenings to remove and replace the cover whenever it may be necessary to expose the internal mechanism of the trunk or reservoir.

Having now so fully explained the several

features of my invention that any one skilled in the art can make a water-closet containing either one or more of the separable parts or features of said invention, in either the 5 precise form shown or under some mere modification, what I claim as new, and desire to secure by Letters Patent, is—

1. In combination with the metallic trunk formed or provided with a projecting stand, 10 *b*, having a groove, *f*, the bowl-neck provided with a bead or circumferential rib, *h*, and the half-collar *C*, preferably grooved at *g*, the whole constructed to operate substantially as and for the purpose hereinbefore set forth.

2. In combination with the trunk *B*, formed 15 with the usual lugs for the attachment of the cover, a cover, *H*, the lugs of which have cut-outs *r* and projections *s*, and screw-bolts *o*, the whole arranged and operating together substantially as and for the purposes set forth. 20

In witness whereof I have hereunto set my hand this 7th day of November, 1885.

JOHN CLIFFORD.

In presence of—
JNO. F. WOLFF,
E. M. FORD.
